UNITED STATES PATENT OFFICE.

HENRY W. MOORE, OF HINGHAM, MASSACHUSETTS, ASSIGNOR TO DUDLEY M. BAKER,
DOING BUSINESS AS CAPE COD SHOP, OF NEW YORK, N. Y.

DESIGN FOR A TANKARD.

Application filed March 29, 1928. Serial No. 26,071. Term of patent 14 years.

To all whom it may concern:

Be it known that I, HENRY W. MOORE, a citizen of the United States, and a resident of Hingham, county of Plymouth, and State of Massachusetts, have invented a new, original, and ornamental Design for Tankards, of which the following is a specification, reference being had to the accompanying drawings, forming part thereof.

Fig. 1 is a view in elevation of a tankard showing my new design; and

Fig. 2 is a plan view of the tankard shown in Fig. 1.

I claim:

The ornamental design for a tankard as shown.

HENRY W. MOORE.
